DESIGN FOR A TEXTILE FABRIC

Frances A. Sheild, Elmhurst, N. Y., assignor to Celanese Corporation of America, a corporation of Delaware

Application July 24, 1941, Serial No. 102,454

Term of patent 7 years

To all whom it may concern:

Be it known that I, Frances A. Sheild, a citizen of the United States, residing at Elmhurst, in the county of Queens, State of New York, have invented a new, original, and ornamental Design for Textile Fabrics, of which the following is a specification, reference being had to the accompanying drawing, forming part thereof.

In the accompanying drawing, the figure is a plan view of a piece of textile fabric embodying my new design.

I claim:

The ornamental design for a textile fabric, substantially as shown.

FRANCES A. SHEILD.
